VEHICLE SIGNAL

Samuel F. Damm and Fred Bjarnov, Niagara Falls, N. Y.

Application December 13, 1930, Serial No. 502,139
Renewed August 10, 1932

10 Claims. (Cl. 116—51)

Our invention relates in general to vehicle signals, and in particular to that type of device used on automobiles or trucks for indicating the intentions or desire of the driver of the vehicle.

5 The principal object of our invention has been to provide a device of this nature which may be operated from the interior of the car, and by which the movements of the human hand may be simulated.

10 Another object has been to provide a device which shall be normally held in its inoperative position in such a manner that it will not be easily seen.

Moreover, our device is so designed that when 15 in one position the hand thereof may be waved backwardly and forwardly, or the hand temporarily locked in a vertical position, while it is being moved to point either to the right or to the left.

20 The above objects and advantages have been accomplished by the device shown in the accompanying drawing, of which:

Fig. 1 is a face view of our device in one of its 25 positions, showing a section through the body of the car to which it is attached.

Fig. 2 is a plan view of the device in another of its positions, showing it as it appears with the roof of the car removed.

Fig. 3 is an enlarged, sectional view, taken on 30 line 3—3 of Fig. 2.

Fig. 4 is an enlarged view of the hand of our device in one of its pointing positions.

Our device comprises a control tube 5, which is slidably supported in a plane parallel to the 35 windshield of the car by a bearing sleeve 6 which is passed through one side of the body 7 of the car and rigidly fastened in place in any suitable manner. Arranged on the interior of the car is a guide bracket 8 which has a bearing 9 at its inner end for the support of the control tube 5. The control tube carries two oppositely arranged 40 detent pins 12 which are engageable when in the position shown in Fig. 1 with slots 13 formed in the inner end of the bearing sleeve 6, whereby the control tube and its associated parts may be held 45 in a definite position, as shown in Fig. 1, and as hereinafter described.

The guide bracket comprises side members 15 which have their inner ends 16 offset so as to 50 provide a pocket 17 in which the pins 12 may be free to move when the tube is rotated. Such rotation of the tube can be accomplished when the pins 12, carried by the tube, are in the positions shown in Fig. 2. The inner ends 16 are 55 provided with right-angled bent portions 18

which are suitably secured to the interior of the car body. The bars 15 of the bracket are so located with respect to the control tube 5, that the detent pins 12 will engage with the upper edges of these bars when the tube is drawn inwardly to its normal position. The relative positions of the pins with the bars 15 when in engagement with the upper edges thereof are shown in Fig. 3. When the pins are in engagement with the upper surfaces of the bars, it is obvious that the tube 5 will be prevented from rotating.

Carried at the inner end of the control tube 5 is an actuating plate 25 which is secured to the end of the tube by means of clamps 26 fastened to the plate. Rotatably carried by the control plate is an actuating shaft 27 which carries an operating handle 28 at one end and an operating gear 29 at the other end. The gear 29 is located on the face of the plate to which the tube 5 is attached. An operating rack 30 is carried by the plate and is slidably mounted in suitable bearings 31. This rack is engageable with the operating gear 29 and is caused to reciprocate by a rotation of the operating gear. A control wire 32 passes through the control tube 5 and has its inner end connected to the operating rack 30 whereby when the rack is reciprocated, the wire will also be reciprocated.

Carried at the outer end of the control tube 5 is a hand plate 35, and the tube is attached to the plate by means of a clamp 36. Rotatably carried by this plate is a hand shaft 37 to the inner end of which is secured a hand gear 38 and to the outer end of which is secured the hand 40 of our device. A hand rack 40 is slidably carried by the hand plate 35 in suitable bearings 41 and the outer end of the control wire 32 is attached to one end of this hand rack, whereby when the wire is moved, the rack will also be moved, thus causing a movement of the hand about the axis of the shaft.

The hand comprises a body portion 42 and a finger portion 43. The finger portion is provided with a hinged plate 44 which is pivotally attached to the body portion by means of lugs 45 and a pin 46. A spring 47 has its end 48 in engagement with the plate 44 of the finger portion, and its other end 49 in engagement with the inner face of the hand portion 42, whereby the finger portion will be held normally in its extended position as shown in Figs. 1 and 2. Carried by the plate 44 is a lug 50 to which one end of an operating link 51 is attached. The other end of this link is pivotally secured to an arm 52 formed on the hand plate 35 and extending 110

some distance beyond the pivot point for the hand shaft 37, whereby when the hand is moved about its pivotal point, the finger portion will be drawn up to a position at substantially right angles to the body portion of the hand, whereby the hand will simulate the thumb and forefinger of the human hand when in a pointing position. A casing 53 is provided for the hand plate 35 and covers the operating mechanism (see Fig. 4). This plate, for clearness of illustration, has been omitted in Fig. 2.

When our device is in its normal, inoperative position, the actuating plate 25 with the operating handle 28 and its associated parts will be in the dotted line position shown in Fig. 1. In such position the actuating parts and hand parts will be in the relative positions shown in Fig. 2, except that they will be drawn inwardly until the pins 12 strike the bearing 9 of the guide bracket 8, or until the actuating plate has been moved to the position shown in dotted lines in Fig. 1. In such position, the hand 39 will lie in a horizontal plane and in which position it will not be readily seen. Starting from the normal inoperative position, when it is desired to put our device into use, the operating handle 28 is grasped and the device is moved axially, thus sliding the tube out through the bearing sleeve 6 until the pins 12 reach the ends 16 of the side plates 15 of the guide bracket, or until they have assumed a position within the recess 17. Up to this point in the axial movement of the tube, the pins 12 have kept the hand in its horizontal position. When, however, the pins 12 are in the recess 17, the handle 28 may be drawn downwardly toward the operator and the hand thereby moved to its vertical operative position. When the parts are in these positions (see Fig. 1) and the handle 28 is properly manipulated, the control tube 5, the actuating plate 35 and the hand plate 25, both of which are carried by the tube, will oscillate and the hand will be waved backwardly and forwardly in a plane parallel to the travel of the car, thus indicating the intention of the operator to stop the vehicle. If it is desired to indicate a right or left hand turn, then the operating handle is first moved, as just above indicated, so as to bring the detent pins 12 within the recess 17 and to bring the hand in a vertical position, after which a further axial movement of the tube 5 will cause the detent pins to enter the slots 13 of the bearing sleeve 6. This will lock the tube from further rotation and hold the hand in a vertical plane. When in this position the operating handle may be moved either to the right or left as desired and as indicated by the dotted line position shown in Fig. 1, which will cause the operating gear 29 to reciprocate the operating rack 30 in the desired direction. This in turn will cause the control wire 32 to be moved within the tube 5 and cause the operation of the hand rack 40 in the same direction. The movement of the rack through the medium of the hand gear 38 will cause the rotation of the hand about its axis. Since, however, the finger portion 43 of the hand is connected by means of the link 51 to the arm 52, the finger portion will be drawn backwardly, as shown in Fig. 4 by the link when the hand is rotated to either of its pointing positions, and thus present to the front or rear of the vehicle only the thumb and forefinger of the hand which has assumed a pointing position.

Obviously, some modifications of the details herein shown and described may be made with-

out departing from the spirit of our invention or the scope of the appended claims, and we do not, therefore, wish to be limited to the exact embodiment herein shown and described, the form shown being merely a preferred embodiment thereof.

Having thus described our invention, what we claim is:

1. In a vehicle signal, the combination with a rotatably mounted control member, of signal means carried by the control member, comprising a rotatably mounted hand movable in a plane parallel to the axis of rotation of the control member, the hand consisting of a body part and a finger part, the finger part being pivotally carried by the body part, and means connecting the finger part with the control member, whereby when the hand is rotated on its axis in either direction, the finger part will be drawn back at an angle to the body part.

2. A vehicle signal comprising a control tube, a bearing sleeve carried by the vehicle for rotatably and also reciprocably mounting the tube, a hand plate carried at the outer end of the tube, a hand pivotally mounted on the plate, a control plate 100 mounted on the inner end of the tube, a pivotally mounted operating handle carried by the control plate, a control wire reciprocably mounted within the tube, and means for connecting the control wire with the hand and with the operating handle, whereby the hand may be moved to the right or to the left upon its axis.

3. A vehicle signal comprising a control tube, a bearing sleeve carried by the vehicle for rotatably and also reciprocably mounting the tube, a hand plate carried at the outer end of the tube, a hand pivotally mounted on the inner end of the tube, a control plate mounted on the inner end of the tube, a pivotally mounted operating handle carried by the control plate, a control wire reciprocably mounted within the tube, and rack and pinion means for connecting the control wire with the hand and with the operating handle, whereby the hand may be moved to the right or to the left upon its axis.

4. A vehicle signal comprising a control tube, a bearing sleeve carried by the vehicle body for rotatably and also reciprocably supporting the tube, a guide bracket carried by the vehicle and having a bearing for the tube, detent pins carried by the tube and movable axially between the bearing sleeve and the bearing of the guide bracket, the guide bracket having bars which engage the detent pins when their axes lie in a horizontal plane, the guide bars having offset inner ends, whereby the detent pins are released from engagement with the bars, permitting rotation of the tube.

5. A vehicle signal comprising a control tube, a bearing sleeve carried by the vehicle body for rotatably and also reciprocably supporting the tube, a guide bracket carried by the vehicle and having a bearing for the tube, detent pins carried by the tube and movable axially between the bearing sleeve and the bearing of the guide bracket, the guide bracket having bars which engage the detent pins when their axes lie in a horizontal plane, the guide bars having offset inner ends, whereby the detent pins are released from engagement with the bars, permitting rotation of the tube, the bearing sleeve being formed with diametrically opposite slots in its inner end for engagement with the detent pins, the axes of the slots being in a vertical plane, indicating means carried at

- the outer end of the tube, and operating means carried at the inner end of the tube. 50
6. A vehicle signal comprising a control tube, a bearing sleeve carried by the vehicle body for 5 rotatably and also reciprocably supporting the tube, a guide bracket carried by the vehicle and having a bearing for the tube, detent pins carried by the tube and movable axially between the bearing sleeve and the bearing of the guide 10 bracket, the guide bracket having bars which engage the detent pins when their axes lie in a horizontal plane, the guide bars having offset inner ends, whereby the detent pins are released from engagement with the bars, permitting rotation 15 of the tube, the bearing sleeve being formed with diametrically opposite slots in its inner end for engagement with the detent pins, the axes of the slots being in a vertical plane, a control wire mounted within the tube, a rotatably mounted 20 indicating hand carried at the outer end of the tube, a rotatably mounted control handle mounted at the inner end of the tube, and means connecting the control wire with the hand and with the handle, whereby the hand may be rotated 25 upon its axis. 7. In a vehicle signal, the combination with a control member, of signal means comprising a hand plate, a gear rack slidably carried by the plate, a hand rotatably carried by the plate, a gear 30 pinion carried by the hand and engageable with the rack, means for reciprocating the rack to cause the rotation of the hand, the hand comprising a body part and a finger part, the finger part being pivotally attached to the body part, a spring means for keeping the finger part in normal position, an arm carried by the hand plate, and means connecting the arm with the finger portion, whereby the finger portion will be drawn 35 backwardly when the hand is rotated in either direction upon its axis. 8. A vehicle signal comprising a control member, signal means carried by the member, said member being so mounted that it can be rotated at substantially the end of its outward movement 40 45 50 55 60 65 70 75
 while the signal means is in one of its indicating positions, and also so mounted that it can be reciprocated axially in non-rotative manner during the major part of its movement outwardly to its rotatable position, a guide bracket for the member, and detent pins carried by the member and engageable with the bracket for keeping the member in its non-rotative position during its major reciprocating movement. 80 85 90 95 100
 9. A vehicle signal comprising a control member, signal means carried by the member, said member being so mounted that it can be rotated at substantially the end of its outward movement while the signal means is in one of its indicating positions, and also so mounted that it can be reciprocated axially in non-rotative manner during the major part of its movement outwardly to its rotatable position, a guide bracket for the member, detent pins carried by the member and engageable with the bracket for keeping the member in its non-rotative position during its major reciprocating movement, and the inner ends of the guide bracket being offset, whereby the pins will be free to rotate when the control member is in one of its outer positions. 105 110 115
 10. A vehicle signal comprising a control member, signal means carried by the member, said member being so mounted that it can be rotated at substantially the end of its outward movement while the signal means is in one of its indicating positions, and also so mounted that it can be reciprocated axially in non-rotative manner during the major part of its movement outwardly to its rotatable position, a bearing sleeve carried by the vehicle body and disposed about the control member, the bearing sleeve being formed at its inner end with a slot and a detent pin carried by the control member and engageable with the slot when at the outer end of its reciprocating movement, whereby the member will be fixed in one position. 120 125 130 135 140 145 150
